WILLIAM WEUSTHOFF AND CHARLES SCHMIDT, OF DAYTON,
OHIO.

Letters Patent No. 92,681, dated July 13, 1869.

IMPROVEMENT IN SEED-WHEELS FOR SEEDING-MACHINES.

The Schedule referred to in these Letters Patent and making part of the same.

To all whom it may concern:

Be it known that we, WILLIAM WEUSTHOFF and CHARLES SCHMIDT, of Dayton, in the county of Montgomery, and in the State of Ohio, have invented new and useful Improvements in Seed-Wheels for Seeding-Machines; and do hereby declare that the following is a full, clear, and exact description thereof, reference being had to the accompanying drawing, making a part of this specification, in which—

Figure 1 is a side elevation of our improved seed-roller;

Figure 2 is a like view of the same, with the front half of the casings removed; and

Figures 3 and 4 are cross-sections of the same, on the lines $x x$ and $y y$ respectively of fig. 1.

Letters of like name and kind refer to like parts in each of the figures.

Our invention relates to a class of seeding-machines in which the seed-wheel is made expansible longitudinally, for the purpose of increasing the capacity of the grooves for containing the seed; and

It consists in the employment of a sheet-metal case, forming a part of the seed-wheel, into which the opposite part is caused to slide, as is hereinafter fully described, by which means the cost of said seed-wheel is materially lessened, and its convenience and desirableness increased.

In the annexed drawing—

A represents the seed-wheel shaft, having secured thereon a cast-metal seed-wheel, B, the body of which is grooved or corrugated longitudinally, while upon one end is a plain cylindrical collar, b.

C represents a casing of sheet-metal, fitted closely to the grooved surface of the wheel B, so as to permit the latter to slide freely in or out thereof.

The outer end of said casing is secured within one end of a cylindrical drum, D, a trifle larger in diameter than the collar b.

Two ribs, c c, extend in parallel lines around the circumference of drum D, near its inner end, and form a groove, the object of which will be fully explained hereinafter.

Pivoted loosely upon the shaft A, immediately against the collar b, is a cylindrical piece, E, corresponding in diameter to said collar, and of sufficient length, in connection therewith, to equal the length of the drum D.

A sheet-metal cover or casing, F, fitted over the cylinder E and collar b, completes the seed-wheel.

The application and operation of this device are as follows:

The shaft A is suitably journalled immediately beneath the seed-box, or hopper, in the bottom of which suitable openings are provided for the escape of the seed.

Beneath each opening is placed a seed-wheel, with one of the side walls of said opening fitted into the groove in the drum D, so that, while said drum is allowed to revolve freely, all lateral motion is prevented.

The opposite wall of said opening fits over the casing F, which has not only a rotary, but also a lateral motion, if desired.

As thus arranged, it will be readily seen that if seed be supplied to the hopper, and the shaft and wheel be caused to revolve, the corrugations or grooves will be alternately filled with seed and discharged, and that the quantity of seed contained in each will depend upon its length.

Such being the case, it is only necessary that suitable means be provided for moving said shaft laterally, in order that the size of said openings, and, consequently, the quantity of grain passed through the seed-wheel, may be regulated, for, as the casing and drum C and D are held in position laterally, and the seed-wheel is secured to the shaft, it will be evident, that as said shaft is moved lengthwise, said seed-wheel will be either pushed into or drawn from said casing and drum, and the length of said corrugations correspondingly changed.

The side wall which fits over the casing F, may be adjusted so closely as to prevent said casing from revolving, and only allow lateral motion, in which event the shaft and collar will revolve independently, causing all wear to be between two surfaces of iron, instead of being between wood and iron.

The advantage of this form of construction consists principally in the great reduction of the cost of the wheel, it being far more easy to fit closely to the corrugations of the wheel the sheet-metal casing, than to fit a cast ring or drum, as is usually done.

Another advantage arises from the increased length of bearing which may be had for the casing covering the corrugated portion of the wheel, as, in consequence of the thinness of the metal used in its construction, so little space radially is occupied by it as to change but slightly the size of said wheel, so that the length of said casing may be equal to that of the grooves, when adjusted so as to contain the smallest quantity of seed.

Having thus fully set forth the nature and merits of our invention,

What we claim, and desire to secure by Letters Patent, is—

The employment of the sheet-metal casing C upon the corrugated surface of the seed-wheel, substantially as and for the purpose shown.

Also, the within-described seed-wheel, consisting of the grooved wheel and collar B and b, casing and drum C and D, cylindrical piece E, or its equivalent, and the casing F, all constructed and arranged to operate substantially as shown, and for the purpose described.

In testimony that we claim the foregoing, we have hereunto set our hands, this 14th day of June, 1869.

WILLIAM WEUSTHOFF.
CHARLES SCHMIDT.
